UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

METHOD OF REFRIGERATOR MANUFACTURE.

Application filed January 31, 1925. Serial No. 6,023.

This invention relates to a method of refrigerator manufacture, the essential object of which is the moulding of a complete refrigerator in one operation. This results in 5 a large saving of time and labor costs since the inner and outer shells are both poured at the same time, dried and hardened at the same time, and when the same comes out of the mould the refrigerator is practically 10 complete, with the exception of hanging on the doors and attaching the hardware.

In the drawings:

Fig. 1 is a vertical section through a refrigerator constructed after my improved 15 method.

Fig. 2 is a section on the line 2—2 of Fig. 1.

Fig. 3 is a section through the moulds showing the refrigerator therein, the cross 20 section taken at right angles to that shown in Figs. 1 and 2.

Fig. 4 is a perspective view of the wooden outer shell.

Fig. 5 is a perspective view of a wooden 25 inner shell.

Fig. 6 is an enlarged sectional detail through a door hinge, showing how the refrigerator hardware may be attached.

This method consists in the building of a 30 wooden outer shell provided with side walls *a*, the top and bottom walls *b* and *c*, respectively, and the front wall *d*. The front wall is provided with the door openings *e* and a groove *f* is cut in the side walls and 35 top wall near the rear of the shell, as clearly shown in Fig. 4. The inner shell *g* is arranged to be telescoped into the outer shell through the opening at the rear of the outer shell, and abuts against the inside face of 40 the front wall of the outer shell, and the same may be correctly positioned therein by means of a suitable jig so that the side walls of the inner and outer shells are spaced from each other. After the inner shell has been 45 correctly positioned with respect to the outer shell, the same may be rigidly secured to the outer shell by nailing the same together where the two shells abut. These nails, shown at *h* in Fig. 3, may obviously be replaced by other suitable fastening means, but I have found that it is much simpler to 50 merely nail the two shells together.

The shells are now placed in a mould. The mould consists of a bottom part *i* and

the side mould parts *j*. A cross member *k* 55 is screwed or otherwise secured to the shell, as shown in Fig. 3, by means of the long screws *m*. This cross member is also secured to the side mould parts by means of the screws *n*, thus floating the shells within the 60 mould and centrally locating the same therein. The inner cores *o* may be inserted through the bottom of the mould and secured to the bottom mould part by means of the bolts *p*, or any other securing means. It 65 will be noticed that these cores (Fig. 3) pass through the door openings in the front wall of the outer shell, and they are of such a size that they will just slip through, thereby assisting in properly positioning the shells 70 within the mould. Other cores *r* may be secured to these cores and the bridge between for the purpose of forming the passageway *s*, shown in Fig. 1, which places the food compartment *t* in communication with the 75 ice compartment *u*. Similarly, the food compartment *v* is connected to the ice compartment by the passageway *w*, which is formed in a similar way.

The stone material is now poured into the 80 mould and covers the outside of the outer shell and the inside of the inner shell by filling up the space between the shell and the mould. It is introduced through the hole 5, in the back 6 of the inner wood shell *g* 85 to fill the space between the inner shell and core.

I preferably use a wood which is rather porous so that as the stone, which is preferably an oxy-chloride cement, is poured 90 therein it will penetrate slightly into the pores of the wood, thereby uniting therewith. I have found that California redwood is very suitable for this purpose, as the same is very porous and is also extremely 95 light. I may or may not use fastening devices *x*, as shown in Fig. 4, which consist of flat-headed nails partly driven into the wooden shell so that the same will become imbedded in the stone.

The stone is allowed to set for approximately 12 hours, which is sufficient time to allow the stone to become extremely hard. The completed refrigerator may now be withdrawn from the mould and the space 105 between the shells filled up with ground cork, or other suitable insulating material, and the back plate *y* (Fig. 2) secured in

place so as to support the rear of the inner shell. The drain pipes 1 and 2 may be readily cast into the refrigerator.

When the refrigerator is withdrawn from the moulds it is a completed article, with the exception of the hanging of the doors and the attaching of the hardware. The small threaded sections of tube designated 10 (Figs. 3 and 4) are screwed into the front of the wooden outer shell and are of sufficient length so as to reach the outside surface of the stone after the stone has been cast. These tubes are internally threaded for receiving the bolts or screws used in attaching the hardware to the refrigerator front.

This refrigerator is extremely light as compared with the solid moulded stone refrigerator of the prior art, as the structure is primarily a wooden structure covered with a layer of stone. This stone layer is relatively thin, as compared to the thickness of the wooden frame, and it is found that the same will not easily chip off and will not crack when subjected to severe strains, as the wood reinforcement provides sufficient tensile strength to resist any strains which the refrigerator may be subjected to when being shipped or knocked about.

One of the advantages of this construction is that it permits the use of the wooden inner and outer shells as part of the mould. The outer shell and inner shell, which are secured together, are floated within the mould in such a way as to space the walls of the outer shell from the mould walls *j*, and to space the walls of the inner shell from the cores *c*. The stone is poured between the outer shell and the mould and between the inner shell and the cores. This obviously eliminates some of the moulds, which are rather expensive, thereby making a large saving in production costs.

In my application Serial No. 18,132, filed March 25, 1925, I claim a moulded core of heat-insulating material in this stone type of refrigerator. The present application is directed to quite a different construction, wherein the core construction is in the form of a fabricated shell or shells of wood, or separate units that have relatively great tensile strength. These not only serve in a measure as heat insulators, but they give shape and strength to the cabinet and prevent the fracture of the stonework.

55. What I claim is:

1. The method of refrigerator or cabinet manufacture, which comprises the fastening together of an inner and outer shell, and the casting of a layer of stone around the outside of the outer shell and the inside of the inner shell.

2. The method of refrigerator or cabinet manufacture, which comprises the fastening together of an inner and outer shell, and the applying of a relatively thin layer of

stone around the outside of the outer shell and the inside of the inner shell.

3. The method of refrigerator or cabinet manufacture, which comprises the fastening together of a wooden inner shell and a wooden outer shell, and the applying of a layer of stone about the outside of the outer shell and the inside of the inner shell.

4. The method of refrigerator or cabinet manufacture, which comprises the fastening together of a wooden inner shell and a wooden outer shell, and the cast-uniting of a layer of stone about the outside of the outer shell and the inside of the inner shell.

5. The method of refrigerator or cabinet manufacture, which comprises the telescoping of an inner shell within an outer shell, the securing of the two shells together in spaced relation, the applying of a layer of stone about the outside of the outer shell and inside of the inner shell, and the filling of the space between the said shells with an insulating material.

6. The method of refrigerator or cabinet manufacture, which comprises the telescoping of an inner shell within an outer shell and securing the same together in spaced relation, the inserting of said shells into a mould provided with cores, the casting of a layer of stone between the mould and outer shell and between the cores and the inner shell, and the filling of the space between said shells with an insulating material.

7. The method of refrigerator or cabinet manufacture, which comprises the telescoping of an inner shell having compartments within an outer shell and securing the same together in spaced relation, the inserting of said shells into a mould and spacing the walls of the outer shell from said mould, the inserting of cores into the compartments of the inner shell and spacing the walls of the inside shell from the said core, the casting of stone between the mould and outer shell and between the inner shell and cores, and the filling of the space between said shells with an insulating material.

8. The method of refrigerator, or cabinet manufacture, which comprises the fitting together of two shells to form a core, and the applying of a relatively thin layer of stone around the outside of the core and the cast uniting of a layer of stone about the inside of the core.

9. The method of refrigerator or cabinet manufacture which comprises fitting together two shells to form a core, one of said shells reinforcing and defining a refrigerator or cabinet wall, and applying a relatively thin layer of stone around the outside of the core, and the cast uniting of a layer of stone about the inside of the core.

In testimony whereof I have affixed my signature.

LLOYD G. COPEMAN.
